UNITED STATES PATENT OFFICE.

JOHN THOMAS, OF PHILADELPHIA, PENNSYLVANIA.

MEANS FOR REDUCING FRICTION BETWEEN SIDES OF SHIPS AND WATER.

SPECIFICATION forming part of Letters Patent No. 532,220, dated January 8, 1895.

Application filed January 5, 1894. Serial No. 495,784. (No model.)

To all whom it may concern:

Be it known that I, JOHN THOMAS, a subject of the Queen of England, residing at Philadelphia, in the county of Philadelphia and State of Pennsylvania, have invented certain new and useful Improvements in Means for Reducing Friction Between the Sides of a Ship and the Water, of which the following is a specification, reference being had therein to the accompanying drawings.

My invention has reference to improvements in steam ships and consists of features fully set forth in the following specification and accompanying drawings forming part thereof.

The object of my invention broadly is to facilitate the passage of a steam ship through the water and whereby the same amount of indicated horse power will propel a ship having my improvement at an increased speed over one that has not.

It is a well known fact in marine engineering circles, that after the development of a certain amount of power required for the propelling of a steam ship through the water at a moderate speed, a largely augmented power is required to accomplish a slightly increased speed. The reason for this largely increased power is the friction between the sides of the ship and the water. This friction of the water pressing against the sides of the ship, carries the water forward with the ship, but at a slower rate of speed. To illustrate more specifically, experiments have demonstrated that with a ship going twenty miles an hour, two feet from the ship the water is going ten miles an hour; four feet from the ship the water is moving two miles per hour; nine feet from the ship one mile per hour and so on in diminished ratio until at a sufficient distance from the ship the water is undisturbed by its movements. The specific object of my invention is to relieve the ship of a portion of this friction and the suction following in its wake and thereby gain increased speed with the same development of power.

I accomplish the objects of my invention by providing a longitudinally moving plate or series of plates. These plates move in the direction opposite to that of the ship and intervene between the side plates of the ship and the water proper. There are two sets of

plates, one on either side of the ship. They are preferably operated by a sprocket wheel, one wheel being preferably used for each plate. The sprockets are held in position by bearings which bearings are fixed to the body of the ship. The horizontally longitudinal lines or contour of the ship are so changed that the wheels themselves present no abnormal resistance to its passage through the water. The sprocket wheels, and therefore the plates, are operated by a mechanism connected with the propeller shaft of the ship, and the wheels are held together by a series of universal joints, one joint between each two sprocket wheels as will be hereinafter more specifically described.

In the drawings like parts are referred to by marks or figures of a corresponding kind in the different views.

Figure 1 is a part side elevation of the rearward or aft portion of a ship having my improvement, and a part longitudinal vertical section through the engines and boilers, showing the connection of the former with the propeller shaft. Fig. 2 is a horizontal sectional plan of the forward and aft end of a ship having my improvement and showing one method of connecting the primary or driving sprocket wheel with the propeller shaft. The idler sprocket wheel and the sprocket for turning the plate, with its idler, in the forward part of the ship are also shown in this view. Fig. 3 is a part forward elevation of a ship, having my improvement and part section on the line $x-x$ of Fig. 2. The sprocket wheels are however shown in elevation. The friction rollers supporting the plates are shown in elevation in this view beyond the section line. Fig. 4 is an enlarged side elevation of the plates with their joints. Fig. 5 is a plan view of one of the sprocket wheels. Fig. 6 is a side elevation of one of the sprocket wheels. The universal joint which operates each successive wheel is also shown in elevation in this figure. Fig. 7 is an end view of the universal joint. Fig. 8 is a longitudinal section of one of the friction rollers which support the plates, showing also a section of the ship plate and the pin or bolt which holds the roller to the plate forming the side of the ship. Figs. 9 and 10 are diagrams illustrative of the principle involved in my invention.

1 is the propeller. 2 is the propeller shaft to which the propeller is secured. 3, 3, 3 are the engine cylinders operating the pistons which drive the propeller shaft. 3' is the 5 thrust block for supporting the end of the propeller shaft. 3², 3², 3², 3² are the foundation supports for the engines, &c. 3³ are the furnaces and 3⁴ is the steam pipe supplying the engine cylinders with steam.

10 Further reference to the well known features of a steam ship is not thought necessary here as they bear no relation to my invention.

In Figs. 1 and 2 I show a bevel wheel actuated connecting mechanism between the propeller shaft and the primary sprocket wheel for operating my plates. In Fig. 3 I show a part bevel wheel and part belt connecting mechanism for the same purpose. The specific form of connecting mechanism for this 15 purpose is not material to my invention, as I do not confine myself to either of those illustrated, or to any other form of special mechanism for the performance of this function.

Referring now to Figs. 1 and 2, 7 is the actuating primary spur bevel gear fixed to the propeller shaft 2. Through the intermediates 5, 6 and 6³ it operates the primary sprocket wheel 8. This sprocket wheel can be of any specific construction consistent with the 20 proper strength and of a shape suitable for the performance of its function. It is best illustrated in Figs. 5 and 6, where it is shown to consist of peripheral flat plates 10², supported on a series of radial arms 10', they being held by a central stem or shaft 10⁵, through an integral suitable collar 10⁶. The outer face of the plates 10² present an angular line to each other. On the apex of the angle thus formed is fixed in a strong and substantial manner a 25 pin 5². There is a series of these pins in the wheel and they constitute the sprocket pins, of the wheel one pin being on the apex of the angle formed between all adjacent plates. The function of these pins 5² is to engage 30 in the hole 19 Fig. 4 of the plates 12, 12, &c., and therefore as the sprocket wheel, shown in Fig. 5, is rotated the plates 12, 12 will be actuated. In Figs. 5 and 6 the plates forming the sides of the sprocket wheel are shown 35 as having a greater vertical length than horizontal and in Fig. 4 the plates 12 are shown as having a greater horizontal length than vertical width. These plates are thus shown to represent two extremes of shape, but in practice, it must be clearly understood that the pitch of the pins 5² on the sprocket wheels 10², Fig. 5, and 8, 9, 10 and 11 Figs. 3 and 2 must correspond to the distance between the 40 holes 19 and 19 of the united plates 12 as shown in Figs. 1 and 4. When these plates 12, 12 as shown in Figs. 1 and 4 are united they become in effect a sprocket chain, endless and continuous. 8 is the primary sprocket wheel communicating motion to its chain. 9 45 is the idler sprocket 10, the turning sprocket wheel and 11 its idler. There is a series of these wheels, as shown in Fig. 3 and, as there

is one chain for each series of wheels, it follows there is also a series of chains or plates. In Fig. 3 is shown the vertical position these 70 wheels occupy with respect to each other. Now the sides of a ship do not form a straight vertical line, as is well known, and, therefore, it is necessary to change the angle of each plate to a different degree. The difference 75 in this inclination will be regulated or determined by the vertical curvature of the ship's sides; but whatever is the inclination of the plate the axes of the sprocket which actuates it must be parallel thereto, in order that the 80 longitudinally moving plate 12 will properly hug the side 10² of the sprocket wheels 10. Both the sprockets 8 and 10 and their idlers 9 and 11 must be constructed and positioned in accord with this law. 85

Between each of the central rods or stems 10⁵, which support the wheels 10, 11, 8 and 9 is a universal joint shown in detail only in Figs. 6 and 7. These joints permit of the shafts rotating at the necessary angles to each other. This joint consists of a pin 20 rigidly fixed to the driving shaft 10⁵ of the wheel which this shaft supports. The arm 25 of the follower has a forked head 22, 22 and these forks are provided with slots 21, in which 95 slots the aforementioned pin 20 plays. This construction admits of the shaft 25, which the shaft 10⁵ actuates, occupying a varying angle in its relation to the said shaft 10⁵. The dotted lines W, W' indicate the variable angular position of these two shafts. The lower end of the shaft 25 is fixed to the shaft it actuates in the same way that the shaft 10⁵ is fixed to the shaft 25. 25 then becomes the driver and its follower is the one it actuates. 100 In this way the entire series of sprocket wheels are driven by one prime mover. This prime mover is the bevel gear 5, shown in dotted lines, Fig. 1. The sprocket wheels 8 and 10 shown in Fig. 2 are the same in construction 110 as are their connections just described; and the idler sprocket wheels 9 and 11 are also the same in construction and further description therefore is not thought necessary. 105

The plates 12, 12, Figs. 1 and 4 consist of 115 flat sheets of steel or wrought iron of moderate gage having a partially semicircular notch 19, shown in Fig. 4. When two of these plates are brought together these semicircular notches form a hole, which hole is engaged by the pins 5² on the sprocket wheel aforementioned. These plates are held together by a male and female joint plate, shown 120 respectively at 17 and 16, and these joint plates are held together by a rivet 18. Being 125 thus joined the plates are permitted to hug the faces of the sprocket wheel and idler previously described.

The arrow A in Fig. 2 indicates the direction 130 in which the ship is moving. The mechanical connections between the propeller shaft and the primary series of sprockets 8 are so arranged that when the ship moves forward this sprocket wheel will rotate and

therefore move the plate in the direction of the arrow o , Fig. 2. Now as this plate or the entire series of plates are in direct contact with the water and intervene between the side of the ship and the water proper friction against the side of the ship will be largely reduced.

The mechanism for actuating the primary sprocket 8 should be so adjusted as to time and speed that the plates 12 will move about as fast as the ship is moving forward. The effect of this will be that any molecule of water in physical contact with such moving plate will not have its position materially disturbed and will not be forced forward to the same degree as it would be if this same molecule of water were in direct contact with the side of the ship. I thus minimize friction against the side of the ship, save fuel and gain speed.

Figs. 9 and 10 are two diagrammatical illustrations of the principle involved in my invention. In Fig. 9 mo represents a molecule of water. Now while the ship moves from the position indicated by the dotted line p' to the dotted line p , the plate 12 moves from the position indicated by the dotted line o^2 to the place indicated by mo , and as the distance from the line p' to the line p is equal to the distance from the line mo to the line o^2 the molecule indicated by the line mo will theoretically not have moved its position, and practically have moved it but a little. It must of course be understood that in speaking of a molecule of water it is considered in a purely representative capacity, for what is true of one molecule is true of all the body of water in contact with the moving plates on either side of the vessel.

Fig. 10 is a diagram illustrating the action of the water when a ship is moving therein not having my improvement applied. In this diagram when the ship is moved from p' to p the molecule is driven from 12^2 to 12^3 and the dotted diverging lines indicate the manner in which the water is carried forward. It is hardly necessary to observe that the arrow o in Fig. 9 indicates the direction in which the ship moves and the arrow o' the direction in which the outer plates move.

In Fig. 2 is shown at 12 and 13 respectively how the plates forming the sides of the vessel proper are shaped in horizontal sectional plan, they being made to conform to the requirements of sprocket wheels fore and aft of the ship.

The plates 12, 12 are held in position by a series of friction rollers 14, 14, 14, 14, 14, 14, &c., shown in Figs. 1 and 3, and illustrated in an enlarged view in Fig. 8. In this figure 14' is the pin or rivet and 14 the friction roller. The friction roller runs freely on the pin 14' but is riveted to the ship plate in a water tight manner. 12 and 13 of this figure are the outer and inner moving or positioned plates.

I do not limit myself to the mere specific details of construction as I could modify them

in various ways without departing from the spirit of my invention.

Having now described my invention, what I claim as new, and desire to secure by Letters Patent, is—

1. A vessel provided with a friction reducing means, consisting of a series of interlinked metallic sections disposed in lateral longitudinal series on both sides of the ship, and a series of plate supporting friction rollers arranged longitudinally in lateral rows. 75

2. A vessel provided with a friction reducing means, consisting of a series of interlinked metallic sections disposed in lateral longitudinal series on both sides of the ship, means for maintaining said plates in a parallel position and means for operating said plates, connected with the motive power of the ship in a direction contrary to the motion of the ship. 85

3. A vessel provided with a friction reducing means consisting of a series of interlinked metallic sections, disposed in lateral longitudinal series on both sides of the ship, a series of sprocket wheels arranged at both ends of the ship, one set of wheels for each plate and each individual set arranged to support and actuate its respective plate, substantially as described for the purpose set forth. 90

4. The combination in a vessel provided with a friction reducing means of a series of interlinked metallic sections disposed in lateral longitudinal series on both sides of the ship, means for supporting said plates in a parallel position means for actuating said plates consisting of a series of primary operating sprocket wheels for each lateral series of plates and each series arranged on a common rotating support, one operating sprocket wheel for each plate, and a connecting mechanism between the motor of the ship and the said sprocket wheel rotating support. 105

5. The combination as a means for arresting friction between the water and the sides of a ship, of a propeller shaft, an operating motor mechanism therefor, a series of longitudinally moving plates, composed of interlinked metallic sections and arranged in longitudinal series on both sides of the ship having a motion contrary to that of the ship and arranged to move along the outer side of the lateral ship plates, and a mechanical connection between the propeller shaft and the said plates. 115

6. The combination as a means for arresting friction between the water and the sides of a ship, of a propeller shaft an operating motor mechanism therefor, a series of longitudinally moving plates composed of interlinked metallic sections and arranged in parallel longitudinal series on both sides of the ship having a motion contrary to that of the ship and arranged to move along the outer side of the ship's lateral plates, means for supporting said plates in a proper normal position, and a mechanical connection between the propeller shaft and said plates whereby on motion being communicated to the propeller 130

shaft the said plates are actuated, substantially as described for the purpose set forth.

7. The combination as a means for arresting friction between the water and the sides
5 of a ship of a series of longitudinally mov-
able sprocket plates said plates composed of
interlinked metallic sections and arranged in
parallel longitudinal series on both sides of
the ship, a series of sprocket wheels for oper-
10 ating said plates and means for operating said

sprocket wheels connected with the motive power of the ship, substantially as described for the purpose set forth.

In testimony whereof I affix my signature in presence of two witnesses.

JOHN THOMAS.
